Primary Examiner — Bridget L Eland(74) *Attorney, Agent, or Firm* — Birch, Stewart, Kolasch & Birch, LLP(57) **CLAIM**

The ornamental design for a mobile phone, as shown and described.

DESCRIPTION

FIG. 1 is a perspective view of a mobile phone showing our new design;

FIG. 2 is a front view thereof;

FIG. 3 is a rear view thereof;

FIG. 4 is a left side view thereof where the right side view is a mirror image;

FIG. 5 is a top plan view thereof where the bottom plan view is a mirror image; and,

FIG. 6 is a front view thereof in a state of operation. The broken lines in FIG. 6 show environmental structure only and form no part of the claimed design.

1 Claim, 6 Drawing Sheets(56)
